DESIGN FOR A BAG

Wesley A. Steelman, Kingston, Pa., assignor to Milprint, Inc., Milwaukee, Wis., a corporation of Delaware

Application July 15, 1942, Serial No. 107,543

Term of patent 14 years

To all whom it may concern:

Be it known that I, Wesley A. Steelman, a citizen of the United States, residing at Kingston, in the county of Luzerne and State of Pennsylvania, have invented a new, original, and ornamental Design for Bag, of which the following is a specification, reference being had to the accompanying drawing, forming part thereof.

In the drawing:

Fig. 1 is a front and end perspective view of a distended bag, embodying my new design; and

Fig. 2 is a rear and opposite end perspective view of the distended bag, embodying my new design.

I claim:

The ornamental design for a bag, substantially as shown.
